UNITED STATES PATENT OFFICE.

RAFAEL GUASTAVINO, OF NEW YORK, N. Y.

MASONRY STRUCTURE.

947,177.

Specification of Letters Patent. Patented Jan. 18, 1910.

Application filed July 31, 1908. Serial No. 446,316.

To all whom it may concern:

Be it known that I, RAFAEL GUASTAVINO, a citizen of the United States, and a resident of the borough of Brooklyn, in the city of New York, in the county of Kings and State of New York, have invented certain new and useful Improvements in Masonry Structures, of which the following is a specification.

10 The present invention relates to masonry structures, particularly such as are constructed from tiles, and has especially in view strengthening means therefor, which will produce the maximum of strength with 15 the minimum of building material and expense.

With the above and other objects in view, the present invention contemplates a masonry structure which may be in the form 20 of arches, domes, walls, or the like, formed of thin tiles having a binding cement or mortar between each course and embedded in such binding material, metal reinforcing rods which extend between the adjoining 25 rows of the tile, whereby said strips are protected from moisture and the atmosphere, and are also protected from any direct heat which would cause them to expand more rapidly than the tiles from which the structure 30 is constructed.

In carrying out the invention, changes in details and structural arrangements may be resorted to, but a preferred embodiment of the same is shown in the accompanying 35 drawings, in which—

Figure 1 is a perspective view of the invention, partly in section, showing the application of the same to a dome. Fig. 2 is a similar view, partly broken away, showing 40 a detail of the crown or central portion of a dome. Fig. 3 is a perspective view, partly in section, showing the application of my invention to an arch. Fig. 4 is a sectional view on the line $x-x$ of Fig. 3. Fig. 5 is a perspective view, partly in section and 45 partly broken away, of a section of an arch. Fig. 6 is an elevation, partly in section and partly broken away, showing my invention as applied to a wall or partition.

50 Like characters of reference designate corresponding parts.

Referring to the accompanying drawings, it will be observed that the present invention has been shown as applied to three 55 forms of masonry structures constructed from tiles, that is, in Fig. 1, a reinforced

tile dome has been shown; in Fig. 3, a reinforced tile arch; and in Fig. 6, a reinforced tile wall; but it will, of course, be understood that these are but three of many 60 forms of structures to which the invention is applicable.

In Fig. 1 of the drawings, the invention has been shown as in use in connection with domes and by reference to the figure, it will 65 be seen that the dome 1 is formed of a plurality of layers or courses of thin flat faced tiles or slabs 2 laid edge to edge and which are so laid as to overlap all joints, the tiles being united through the medium of suitable 70 binding cement, mortar or the like, 3. Reinforcing or strengthening rods 4 are embedded in the binding material in the joints between the tiles, so that the bonded strength of the whole structure is not in any way 75 lessened by the introduction of these rods. The rods are preferably of a spiral form, to secure an interlocking engagement with the binding material, and are adapted to extend entirely around the dome and are of such 80 dimensions in cross section that they can be readily introduced between the layers of tile without disturbing the general method or scheme of laying and bonding the tiles to each other. They are also of such size 85 that the workman can readily bend or conform them to the form of the structure without putting any undue strains upon the materials during the course of construction. It is not essential that these rods should be in 90 the form of continuous bands extending all around the dome, but they may be formed of shorter rods with overlapping ends, and yet give substantially the same strength 95 through the structure. As the greatest outward thrust of a semicircular dome is near the base, I place the metal rods extending around the dome closer together near the bottom thereof, as shown in Fig. 1; varying 100 the size of the rods and increasing the distance between them from the bottom of the dome upward, according to the strains to which the various portions of the dome are subjected. Whenever necessary to do so on account of strains to which the dome is to be 105 subjected, I also place metal strips or rods 5 radiating from the center of the crown of the dome, as shown in Figs. 1 and 2. This I find necessary where a superstructure is mounted upon the top of the dome, subjecting the crown to shearing or crushing 110 strains, and the cross section of these radiat-

ing rods 5 I may decrease from the center of the dome outward, as circumstances may require, thereby obtaining the desired strength with the minimum amount of metal and material.

In Fig. 3, I have shown a tile arch 6 consisting of four layers of thin overlapping tiles 2 bonded together by cement, mortar or other suitable bonding material, 3, resting upon a base or supporting wall 7. Reinforcing or strengthening rods 8 are embedded in the bonding material, said rods extending entirely across the span of the arch and into the masonry structures or walls 7. These rods may be either a single rod extending from base to base of the arch, or consist of a number of rods with overlapping ends. As shown in Fig. 5, I may also employ transverse rods 9 which are embedded in the bonding material between the courses of tile, for the purpose of preventing the arch from separating laterally. As shown in the drawings, these rods may be of such a size and number as to give to the arch the requisite strength. As shown in Fig. 5, I may also employ rods 13 running through the arch from near the lower face toward the upper face. These rods 13 I find necessary where the arch is of considerable thickness and carries a heavy load, in order to overcome the tendency of such arches to shear or separate between the courses of tiles.

In Fig. 6, the invention has been shown as in use in connection with walls or partitions, 10, also formed of a plurality of layers or courses of tiles 2, which are laid on edge so as to overlap all joints, the tiles being united through the medium of suitable binding cement, mortar or the like, 3, in which are laid vertical reinforcing or strengthening rods 11, and horizontal reinforcing or strengthening rods 12, such rods 11 and 12 being of such size and so spaced from each other as to give to the wall or partition the desired strength without increasing the thickness of the wall. By the means described, I am able to entirely conceal the strengthening rods in all the structures shown, and to lay the tiles without disturbing the general method or scheme of the structure, and without in any way lessening the bonded strength of the structure, and the strengthening rods are protected from moisture and from the atmosphere, and also from heat, which is particularly desirable in case of fire. I am also able to increase the size and strength of partition walls without increasing their thickness, and find that it is possible to construct arches or domes having spans or diameters of ninety to one hundred feet from three or four courses of thin tiles, which was not heretofore possible. I am aware that heretofore in the construction of tile arches, iron beams with flanges I or

T shaped in cross section have been used, together with cross anchors consisting of rods running through the web of such beams. These beams have, however, been necessarily of such depth that the webs thereof have extended up into the tile material so far that a number of layers of tile have necessarily abutted against the web of such beams and thereby separated the arch or structure into sections, thus to a large extent disturbing the lateral bonded strength and homogeneity of the mass. These I or T beams heretofore used have also been provided with a web of very considerable depth, far greater than the load which they were to carry required, in order to prevent undue deflection of the beam through its own weight when placed in position. For the sake of economy, it was also found necessary to space them at considerable distances from each other. This resulted in the production of a structure of unequal strength, the strongest part of the structure being adjacent to the beam and the weakest part being at the greatest distance therefrom. It was also found necessary to finish or complete such beams at the mill or shop where they were constructed and their conformation could not be in any way changed in order to adapt them to unusual conditions arising during the progress of the work, and they were objectionable because they were expensive and very difficult to manipulate, and they proved impracticable for use in large domes, domic vaults or groin arches, and many other structures.

All of these difficulties and disadvantages I have overcome through my invention.

It will be observed that in all embodiments of the invention the distinctive thought resides in a plurality of parallel superposed courses of thin tiles, the tiles in each course being laid edge to edge and arranged to break joints crosswise of the structure, in connection with binding material between the tile in the separate courses and also between the edges of adjoining tiles.

Claims:

1. A reinforced masonry structure, comprising a plurality of superposed courses of thin tile slabs, the slabs in each course being flushly laid edgewise with their thin edges arranged edge to edge, said slabs being also so disposed as to break joints cross-wise of the structure, binding material between the tile slabs in the separate courses, and also between the edges of adjoining tile slabs, and reinforcement lying in the binding material.

2. A reinforced masonry structure comprising a plurality of superposed courses of thin tile slabs, the slabs in each course being laid edge to edge and arranged to break joints cross-wise of the structure, binding material between the tile slabs in the sep-

arate courses and also between the edges of adjoining tile slabs, reinforcement lying in the joints between the courses, and reinforcement lying in the joints between the edges 5 of the tile slabs.

3. A reinforced masonry arch, comprising a plurality of superposed courses of thin tiles, the tiles in each course being laid edge to edge and arranged to break joints cross- 10 wise of the structure, binding material between the tile in the separate courses and

also between the edges of adjoining tiles, and reinforcement lying in the joints between the courses and also in the joints between the edges of the tiles.

15

Signed at the borough of Manhattan in the city, county and State of New York, this 17th day of July, A. D. 1908.

RAFAEL GUASTAVINO.
